INVENTOR:

UNITED STATES PATENT OFFICE.

FRANK B. COOK, OF CHICAGO, ILLINOIS.

ELECTROTHERMAL PROTECTOR.

No. 891,463.

Specification of Letters Patent. Patented June 23, 1908.

Application filed May 23, 1907. Serial No. 375,282.

To all whom it may concern:

Be it known that I, FRANK B. COOK, a citizen of the United States of America, residing at Chicago, in the county of Cook and State 5 of Illinois, have invented a new and useful Electrothermal Protector, of which the following is a specification, reference being had to the accompanying drawings, illustrating same.

10 My invention relates to protectors and protective apparatus for protecting electrical circuits and apparatus from abnormal currents and potentials of electricity.

The principal objects of my invention are 15 to provide a simplified and compact protector of the character specified; to provide improved means for grounding the line circuit upon the operation of the protector; to provide improved means for mounting the 20 lightning arrester of the protector in place; to provide improved means for operating the thermal protector of the apparatus upon excessive heating; to provide improved means whereby the thermal protector may be readily 25 reset after operation for another operation; and to provide improved means for closing an alarm circuit when the thermal protector operates.

Other objects will be apparent from the 30 following specification.

By reference to the accompanying drawings illustrating the preferred form of my invention, Figure 1 is a plan view of a pair of 35 duplicate sets of the protective apparatus mounted upon opposite sides of a ground plate; Fig. 2 is a front edge elevation of Fig. 1, showing a series of lightning arresters placed against the ground plate; Fig. 3 is a longitudinal cross-section of the thermal protector and lightning arrester shown in Figs. 40 1 and 2, with portions shown in elevation; Fig. 4 is a detail view of the alarm spring used in the protective apparatus; and Fig. 5 is a detail view of the line spring used in the 45 protective apparatus.

Like characters refer to like parts in the several figures.

In the drawings, line springs 1 1, alarm 50 springs 2 2, and switchboard springs 3 3, are all mounted on ground plate 4 by bolts 5 5 in the usual manner, the line terminals 6 and 7 being arranged on one side of the ground plate and the switchboard terminals 8 and 9 being arranged on the opposite side of the

ground plate. A bushing 10 is placed between springs 1 and 2 so that spring 2 may have a slight tension toward spring 1 and, at the same time normally remain out of contact with spring 1, as shown on the left of Fig. 1. It is desirable to have this tension in 60 spring 2 so that in assembling it is not required to accurately adjust spring 2 to normally keep it out of contact with springs 1 and 3 as shown on the left of Fig. 1.

The thermal protector comprises an 65 enclosing shell 11 containing a resistance element 12, a contact plate 13 and a terminal 14, the parts 12, 13 and 14 being suitably insulated from the casing 11 and the resistance element 12 making contact with end 15 70 of the casing. This construction is shown, described and claimed in my copending application for Letters Patent on Electro-Thermal Protector, Serial No. 316,153, filed May 10, 1906. The terminal 14 is provided 75 with a head 16 against which spring 3 presses as shown in Fig. 1, to provide an operable contact for testing purposes. The casing 11 is provided with a pin 17 extending from the end 15 thereof, which pin extends through 80 a hollow neck portion 18 extending from the end of a metallic cup-shaped portion 19 which incloses the said shell 11 and which is cemented to the portion 11 at 20 by a suitable heat-susceptible cement, preferably a 85 metallic solder. The neck portion 18 guides the pin 17 and is provided with an annular flange 21 thereon which bears against the outer carbon block 22 of the lightning arrester so as to make good electrical connection therewith and hold the carbons 22 and 23 and the dielectric 24 thereof in place 90 against the ground plate 4, the latter electrically engaging the carbon 23. The carbon 22 is provided with a central hole therein 95 in which the neck portion 18 extends, preferably as shown in Fig. 3, so that the pin 17 may freely move through the neck portion 18 without engaging the carbon 22 and being hindered thereby. Line spring 1 engages 100 the neck portion 18 in the annular recess 25, the spring 1 having a slot 26 for receiving the neck portion and a split 27 extending therefrom to cause the portions along the slot 26 to firmly grip the neck portion. The 105 carbon 23 when inserted into the apparatus rests in a cut-out portion in the end of insulating strip 28, which keeps the carbon 23 in

alinement, the latter being provided with a large hole 31 therein through which the pin 17 extends and which prevents the pin 17 from ever coming into engagement with the carbon 23. The alarm spring 2 is provided with a contact 29 adapted to engage line spring 1, and with a contact 30 adapted to engage switchboard spring 3, when the thermal protector operates.

10 It will be seen from Fig. 2 that the carbon blocks 23 23 in a series of lightning arresters mounted along the ground plate 4, fit in close to each other so as to help keep them in alinement. The line carbons 22 22 are 15 somewhat smaller than the carbons 23 23, to provide clearance between them as shown in Fig. 2.

The operation of the apparatus is as follows: When an abnormally large current 20 traverses the heat-producing element, or resistance element, 12 of a thermal protector, such current generally coming from a line spring 1 and passing through the thermal protector to the switchboard spring 3, the 25 resistance element 12 produces heat, which heat, when sufficient, softens the heat-susceptible material 20 which then allows the casing 11 to move within the cup 19. Now the switchboard spring 3 bearing against the 30 head 16 pushes the thermal element as a whole farther into the cup 19 until the end of pin 17 engages the ground plate 4 and thereby grounds the line spring 1 which switches the objectionable current off to 35 ground through the pin 17 and the ground plate 4, thereby diverting the said objectionable current from the thermal protector and from the circuit and apparatus connected with spring 3. The operation of 40 spring 3 also causes same to engage contact 30 and operate spring 2 until contact 29 thereof engages spring 1, thus closing a suitable alarm circuit between springs 1 and 2 to give a signal in the usual manner to indicate that the apparatus has operated, and 45 also preferably grounding the switchboard spring 3. Spring 2 is preferably thin and is preferably cut away at 32 so that after contact 29 engages spring 1, the portion 30 may 50 be still farther depressed by spring 3 until the pin 17 firmly engages the ground plate 4. When it is desired to reset the thermal protector for another operation, the same may be heated in any suitable manner, either 55 mechanically or with an electric current, and the parts properly restored to the position shown in Fig. 3, the heat-susceptible material 20 being then allowed to cool and thereby cement the portions 11 and 19 together 60 as originally.

Electricity of high potential coming to the protector over line spring 1, when the thermal protector is set passes through the carbon 22, the dielectric 24 and the carbon 23 65 to ground through the ground plate in the

usual manner, thus being diverted from the thermal protector and from the circuit and apparatus connected with spring 3.

If desired, the alarm springs 2 2 may be done away with entirely, where same are not required, without in any manner affecting the remainder of the protective apparatus or the operation and functions thereof.

I do not wish to limit this invention to the particular details of construction as herein shown, either in the apparatus as a whole or in any of the parts thereof, as many modifications may be made in same without departing from the scope of the invention. Neither do I wish to limit this invention to any particular cementing material in the thermal protectors, nor to the particular switching of the line circuits as herein shown.

What I claim as my invention and desire to secure by Letters Patent is:

1. In apparatus of the character described, a ground plate, spring members mounted upon the ground plate near one edge thereof and suitably insulated from each other, a lightning arrester comprising a pair of electrodes held against the other edge of the ground plate by one of the said springs, a thermally-operable device held in close proximity to the lightning arrester by the said springs, and an operable member extending through the electrodes of the lightning arrester to engage the ground plate when the thermally-operable device is operated, whereby one of the said spring members is grounded.

2. In apparatus of the character described, a ground plate, a lightning arrester comprising two carbon disks one of which is held against the ground plate, a thermally-operable device held in close proximity to the lightning arrester, means for operating the thermally-operable device upon excessive heating, and a pin projecting from the said thermally-operable device through the electrodes of the lightning arrester to engage the ground plate when the thermally-operable device is operated, for purposes substantially as described.

3. In apparatus of the character described comprising a ground plate and spring members mounted thereon, a lightning arrester inserted into the apparatus near one edge of the ground plate and engaging the latter, a strip of insulation lying along the ground plate to limit the insertion of the lightning arrester, and a thermally-operable device carried by the said spring members and having a pin extending into the lightning arrester, the said pin being operated by one of the spring members to contact the ground plate upon abnormal current conditions in the thermally-operable device, whereby one of the said spring members is grounded.

4. In apparatus of the character described, a ground plate, a pair of spring members

mounted thereon and suitably insulated from each other, a thermally-operable device carried by the said pair of spring members and having a contact member adapted to engage 5 the ground plate upon the operation of the device, and a third spring member located between the said pair of springs, having tension toward one of the springs of the pair but held out of engagement therewith by a suitable bushing, and adapted to engage one of the latter when the said device operates, to close a circuit for purposes substantially as described.

5. In apparatus of the character described, 15 a ground plate, a lightning arrester and a thermally-operable device near one edge of the ground plate arranged perpendicular to same, one of the electrodes of the lightning arrester engaging the ground plate, and a 20 contact member extending from the thermally-operable device through the lightning arrester to contact the ground plate upon abnormal current conditions, to ground a circuit.

25 6. In apparatus of the character described, a ground plate, a lightning arrester, an electro-thermally-operable device, means for operating the said device upon excessive heating, and a contact member extending 30 from the said device through the lightning arrester to contact the ground plate when the said device is operated, substantially as described.

7. In apparatus of the character described, 35 a ground plate, a lightning arrester, an electro-thermally-operable device, said lightning arrester being held against said ground plate, and a contact member extending from the said device and arranged substantially 40 perpendicular to the ground plate, said contact member being arranged to extend through the lightning arrester and contact the ground plate upon the operation of the said device, to ground a circuit.

45 8. An electrothermal protector of the character described comprising a ground plate, a thermally-operable device arranged near one edge of the ground plate, the said device comprising a heating element and suitable 50 terminals therefor, a metallic cup-shaped portion inclosing the active portion of the heating element and secured by solder thereto to normally hold the heating element from operating, and a contact member extending 55 from one of the said terminals through the cup-shaped portion and adapted to contact the ground plate upon the operation of the device, substantially as described.

9. An electrothermal device comprising a 60 heating element and a suitable terminal therefor, a metallic casing inclosing the heating element and terminal, making contact with the heating element and being insulated from the terminal, whereby the said casing, 65 heating element and terminal are connected

in series, a cup-shaped portion in which the whole is placed, heat-susceptible material between the cup-shaped portion and the casing, normally holding the latter against movement in the cup-shaped portion, a neck portion 70 extending from the cup-shaped portion, and a pin extending from the said casing through the neck-portion to operate to control a circuit upon the operation of the device, the said device being operable when the 75 heat-susceptible material is softened by excessive heating.

10. An electrothermal protector comprising a heating element having a spindle extending from either end thereof, a metallic 80 sleeve surrounding the active portion of the heating element and normally secured thereto by heat-susceptible material, and means for moving the heating element longitudinally in the said sleeve when the heat-susceptible material is softened, whereby one of the said spindles is caused to control a circuit.

11. In apparatus of the character described, a lightning arrester comprising a 90 pair of carbon disks with a suitable dielectric interposed therebetween, an electrothermal device associated with the said arrester, a hole through the lightning arrester, and a contact member extending from the electro- 95 thermal device through the lightning arrester, said contact member being utilized to control a circuit upon the operation of the said device.

12. In apparatus of the character described, a lightning arrester comprising a pair of carbon disks with a suitable dielectric, interposed therebetween, a hole through the center of the said disks, a cup-shaped portion having a flange bearing against one of the 100 said disks and a neck extending into the latter said disk, a heat-cartridge contained in the said cup and normally held against operation by heat-susceptible material, a pin extending from the said cartridge through the 105 said flange and neck and into the said hole in the lightning arrester, and means for operating the heat-cartridge within the said cup upon excessive heating to operate the said pin through the lightning arrester to control 110 a circuit.

13. In apparatus of the character described, a ground plate, a lightning arrester and a thermally-operable device mounted 120 near one edge of the ground plate, a pin extending from the thermally-operable device into the lightning arrester, and a spring member bearing against the said device to operate the said pin and cause same to contact the ground plate, the contact between the said device and the said spring member being openable for testing purposes.

14. An electrothermal protector of the character described comprising a heating element, a sleeve inclosing the heating element 130

and in which the latter is operable upon excessive heating, a terminal extending from the heating element, and means on the said terminal adapted to be pulled upon to operate the heating element in the said sleeve to reset the protector for operation when same is properly heated.

15. An electrothermal protector of the character described comprising a sleeve, a 10 heating element within the said sleeve normally secured thereto by heat-susceptible material, a terminal portion extending from the heating element out of either end of the sleeve, means for operating the said heating 15 element longitudinally in one direction in the said sleeve, upon excessive heating, to cause one of the said terminal portions to control a circuit, and means on one said terminal portion adapted to be pulled upon to operate 20 the said heating element longitudinally in

the opposite direction in the said sleeve, when properly heated, to reset the parts of the device to normal position for another operation.

16. A lightning arrester comprising a line electrode and a ground electrode, a ground plate engaging the ground electrode, the said electrodes having a hole therethrough, a thermally operable device and a contact member extending from the said device through the said hole to contact the ground plate when the said device is operated. 25 30

As inventor of the foregoing, I hereunto subscribe my name in the presence of two subscribing witnesses, this 20th day of May, 1907.

FRANK B. COOK.
